UNITED STATES PATENT OFFICE.

JOSEPH M. ATKINSON, OF BALTIMORE, MARYLAND, ASSIGNOR TO OPPENHEIM, OBERNDORF & CO., A FIRM COMPOSED OF ELI OPPENHEIM, ISAAC A. OPPENHEIM, AND DAVID OBERNDORF, ALL OF BALTIMORE, MARYLAND.

SHIRT AND DRAWERS.

1,113,924.

Specification of Letters Patent. Patented Oct. 13, 1914.

Application filed September 21, 1912. Serial No. 721,540.

To all whom it may concern.

Be it known that I, JOSEPH M. ATKINSON, a citizen of the United States, residing at Baltimore, in the State of Maryland, have 5 invented certain new and useful Improvements in Shirts and Drawers, of which the following is a specification.

This invention relates to an improved garment for men's wear—comprising a certain combination of over-shirt and drawers.

The object of the invention is to provide an over-shirt and drawers united in one garment, for men's wear, said garment being specially constructed to insure that the front 15 or bosom part of the shirt when on the person will be kept drawn smoothly. This is done by providing means to cause a close fit of the drawer legs at the crotch or at the inner side of each thigh.

20 The improved garment is illustrated in the accompanying drawing in which,

Figure 1 is a front view of the united garment. Fig. 2 is a vertical section down the center of the garment along the flap of the 25 front opening. Fig. 3, is a front view of the two legs of the garment showing that the legs are completely separated along a vertical line at the crotch. Fig. 4 is a back view of the lower part of the garment, including 30 the seat portion and the legs.

The united over-shirt and drawers garment should be made preferably of suitable textile fabric.

The shirt part shown in the drawing has 35 the front designated by the numeral, 1; and the back, 2, the shoulder seams, 3, neck-band, 4, and sleeves, 5, which are provided with cuffs, 6. The two legs of the drawers part have their fronts designated, 7, and 40 their backs, 8; the legs are a continuation downward of the same pieces of textile fabric that compose the shirt-front and back. The drawer legs are completely separated from each other at the crotch, 9; this separation 45 makes the crotch open at the front, underneath and up at the back to, 10, as clearly shown in Figs. 3 and 4. The garment has a front opening, 11, that commences at the neck-band and extends centrally down the shirt-bosom, 12, and opens 50 into the said open-crotch, 9. This vertical front opening is closed by buttons, 13. It

will thus be understood the front opening, 11, that commences at the neck-band, and also the open-crotch, 9, that extends from 55 said front opening up the back to, 10, separates the right and left sides of the garment except at that part, 14, of the back where the said two sides are joined from the neck-band, 4, to the point, 10, see Figs. 2 and 4. 60

The front fabric, 1, and back, 2, of the garment are united by side seams, 15, from the arm-hole downward. The front, 7, and the back, 8, of each leg has an inseam, 16, which commences at the bottom, 17, of the 65 leg but does not extend all the way up to the crotch part. A V-shaped piece of elastic material, 18, is inserted above the inseam, 16, of each leg, the broadest part, 19, of said elastic material being uppermost and forming 70 a part of the crotch edge, 9, of the drawer leg. This V-shaped insert of elastic material at the thigh or crotch part of each leg of the drawers serves, in a united shirt and drawer garment, a special purpose 75 which it is one of the objects of this invention to achieve, namely, to cause a close fit of the drawer leg at the crotch of a person, or at the inner side of each thigh, and by such close fit insure a slight down-pull on 80 the front or bosom-part of the shirt that will keep said bosom down smoothly; the V-shaped insert, 18, being of elastic material will avoid an unpleasant degree of tightness on the flesh of the wearer. 85

Having thus described my invention what I claim and desire to secure by Letters Patent is:—

An overshirt and drawers for men's wear, consisting of the front having two vertical 90 pieces of textile fabric—a right and left—the top of both pieces commencing at the shoulder-seams and extending downward therefrom to the bottom of the two legs, and said two front pieces separated from each other by a vertical opening that includes the neckband and extends to and forms an open-crotch; the back of the garment extending 95 from the shoulders to said leg-bottoms, said back portion being of the same length from the shoulder-seam down as said front portions, and each leg of said garment provided with a separate V-shaped piece of elastic material inserted in the inseam of the leg, the 100

broadest part of said V-shape being uppermost and forming an elastic edge to said open-crotch, whereby the elastic edges of said open-crotch contacting with the inner part of the wearer's thigh will produce a slight down-pull on the front or bosom part of the garment and keep same drawn smoothly.

In testimony whereof I affix my signature in presence of two witnesses.

JOSEPH M. ATKINSON.
